UNITED STATES PATENT OFFICE.

FOREST CHENEY, OF CHICAGO, ILLINOIS, ASSIGNOR TO CHENEY TALKING MACHINE COMPANY, OF CHICAGO, ILLINOIS, A CORPORATION OF ILLINOIS.

CONTROL MEANS FOR SOUND-REPRODUCING MACHINES.

1,415,525.

Specification of Letters Patent. Patented May 9, 1922.

Application filed November 14, 1917. Serial No. 201,921.

To all whom it may concern:

Be it known that I, FOREST CHENEY, a citizen of the United States, and resident of Chicago, in the county of Cook and State 5 of Illinois, have invented certain new and useful Improvements in Control Means for Sound-Reproducing Machines, of which the following is a specification.

This invention relates to sound reproducing machines, and more particularly to 10 control means therefor.

One of the objects of the invention is to control the operation of a sound reproducing machine in an improved manner.

15 Another object of the invention is to improve means for automatically stopping the operation of a sound reproducing machine.

Another object is to provide control means 20 for sound reproducing machines adapted to meet the various requirements for successful use.

Generally speaking, these and other objects are accomplished by providing in a sound reproducing machine, the combination 25 of a turn table, a motor for actuating said turn table, and means for interrupting the actuating medium for said motor for causing the turn table to stop.

The invention is illustrated on the accompanying sheet of drawings in which,

Figure 1 is a side elevation, partly in section, of a portion of the sound reproducing machine embodying my invention;

Figure 2 is a sectional view taken in the 35 plane of line 2—2 of Figure 1 showing, among other things, the motor circuit complete for driving the turn table;

Figure 3 is a fragmentary sectional view of the same showing the motor circuit interrupted for causing the turn table to stop, and,

Figure 4 is a sectional view taken in the plane of line 4—4 of Figure 2.

The various novel features of the invention will be apparent from the following description and drawings, and will be particularly pointed out in the appended claims.

Referring to the figures of the drawings, 50 it will be noted that I have shown a tone arm 5 and a turn table 6 of a sound reproducing machine. The tone arm 5 is provided with a downwardly extending cylindrical portion 7 adapted to rotate within the

tubular portion 8 attached to the base 9 of 55 the machine. Around this tubular portion 8 is rotatably arranged a sleeve 10, which is connected to the cylindrical portion 7 of the tone arm by pins 11 and 12 so that the sleeve turns with the tone arm. Slots are formed 60 in the tubular portion 8 to allow the pins to move within the desired arc of movement of the tone arm. To this sleeve 10 is connected by means of the pin 11, an arm 13, which in the form of construction illustrated, consists 65 of a thin metal stamping. This arm is provided with a curved portion 14 of the same curvature as the sleeve 10 and also a lateral projection 15 adapted to engage another portion of the sleeve 10 in order to prevent 70 lateral movement of the arm 13 relatively to the sleeve 10. Vertical movement of the arm is prevented by the inwardly turned projections 16 which engage the upper edge of the sleeve 10. The outer end 17 of this 75 arm operates the stop mechanism as will be hereinafter described.

The stop mechanism includes a base 4 on which is arranged a member 18 pivotally mounted on the base 4 at 19 and carrying 80 the movable contact 20 of a switch having a pair of stationary switch contact members 20^a carried by a block of insulation secured to the base 4. A spring 21 tends to turn the member 18 in a manner to carry the movable 85 switch contact 20 out of engagement with the stationary contact members 20^a to break the electric circuit 22 of the propelling motor 22^a suitably geared to the turn table, the switch contacts being in engagement 90 with each other, as shown in Figure 2, for completing the motor circuit whereupon the motor drives the turn table 6 and the switch contacts being out of engagement with each other, as shown in Figure 3 to break the 95 motor circuit for causing the turn table 6 to stop. A lever 37 having a knurled knob 38 is connected to the switch carrying member 18 for moving the latter manually against the tension of the spring 21. The 100 movable switch member 20 after movement by the lever 37 to complete the motor circuit is held in such position by means of a latch 23, the shoulder 24 of which engages a shoulder 25 of the contact carrying member 18. The latch is operated by means of a trigger 105 or lever 26. The end of the trigger 26 loosely engages a slot 39 in the end of the

latch 23 so that the trigger and latch may move slightly independent of each other as a result of the lost motion connection. The lost motion connection between the trigger 5 26 and latch 23, though slight, permits the machine to run a little longer than the normal stop setting would seem to indicate. In this way there is no chance for the machine to stop automatically until the record is 10 completely played. Movement of the trigger and latch away from the contact carrying member 18 is limited by a stop 40, as shown in Figure 3.

As stated before, in Figure 2 the various 15 parts are shown in their relative positions with the switch contacts 20 and 20^a in engagement with each other to complete the motor circuit for driving the turn table, and in Figure 3 parts are in such relative 20 positions that the switch contacts 20 and 20^a are out of engagement with each other to interrupt the motor circuit. In this latter position the end of the latch engages a 25 second projection 27 on the contact carrying member 18, which projections prevent the spring 21 from functioning to cause movement of the member 18 to close the motor circuit. The trigger 26 is pivoted at 28 about which point a lever 29 also turns. 30 The lever 29 is provided at its outer end with a knurled knob 41 adapted to be engaged by the end 17 of the arm 13 as the latter is moved by the tone arm toward the left, as shown in Figures 2 and 3. The trigger 35 26 and lever 29 are connected frictionally so that their relative positions may be adjusted. For this purpose the trigger is provided with a right-angle extension 30 carrying at its end a bolt 31. The lever 29 40 is also provided with an extension 32 overlying the extension 30 and having a segmental slot 33 formed in its end portion. The bolt 31 passes through this slot and as the head 34 of this bolt is retracted by a spring 35 45 surrounding the bolt 31, the extensions 30 and 31 are held in frictional engagement with each other, as will be evident from Figure 4. This segmental slot 33 allows of adjustment between the lever 29 and the 50 trigger 26. The tension of the spring may be varied as desired by means of the nut 45 on the bolt 31. The trigger 26 is provided with a hooked projection 36 adapted to engage one end of the spring 21. This 55 spring tends to hold the trigger and thereby the latch 23 in engagement with the contact carrying member 18. It will be observed that the spring 21 actuates both the contact carrying member 18 and also the 60 trigger 26 and latch 23.

In the operation of the device, the lever 29 is first moved to the left, as viewed in Figures 2 and 3, an amount such that the tone arm may be moved to bring the needle into 65 engagement with the last groove or substan-

tially the last groove of the record without causing the arm 13 to engage the lever 29. The tone arm then is moved to the extent that the needle engages with the last groove. The lever 29 is then moved to the right until 70 it engages the arm 13 thereby leaving a slight space between the trigger 26 and the outer wall of the slot 39 to prevent premature stopping of the machine. As the movement of the trigger 26 is limited by the stop 75 40 the arm 29 is moved relatively to the trigger to allow the tone arm 5 and arm 13 to move for setting the machine for proper stopping thereof. The tone arm is then moved to bring the needle in engagement 80 with the groove at the beginning of the record.

To start the turn table rotating the lever 37 is moved to the left, as shown in Figures 2 and 3. As soon as the shoulder 25 of the 85 member 18 is moved beyond the shoulder 24 of the latch the latter is moved upwardly by the action of the spring 21 on the trigger 26 so the movable contact 20 of the switch is moved into engagement with the stationary contacts 20^a to complete the motor circuit. This movement of the latch and trigger causes a slight movement of the lever 29 to the right. When the needle has reached the end of the record, the end 17 of the arm 90 13 contacts with the knob 41 of the arm 29 and gradually moves the latter and trigger 26 to the left without imparting any motion to the latch 23 until the safety lost motion is taken up and then the latch is tripped and 95 the movable electric contact 20 snapped out of engagement with the stationary contacts 20^a to interrupt the motor circuit thereby causing the turn table to cease rotating. Not only is the circuit of the electric motor 100 interrupted to stop the rotation of the turn table, but also the turn table is stopped automatically in a manner such that the record will be completely played before the machine is stopped. 110

It is apparent that there may be various modifications of the invention herein particularly shown and described, and it is my intention to cover all such modifications which do not involve a departure from the 115 spirit and scope of the invention as set forth in the following claims.

I claim:

1. In a sound reproducing machine, in combination, a motor for actuating a record, 120 a switch in the motor circuit, a latch for holding said switch in closed position, tripping mechanism for operating said latch adjustable with respect to said latch to time the occurrence of the tripping action, said 125 tripping mechanism including two relatively movable members, one of which members engages said latch, a projection secured to the tone arm and arranged to engage the other member of said tripping members 130

- under certain conditions, and a spring for actuating the tripping mechanism to open said switch when one member of said tripping mechanism is engaged by said projection.
2. In a sound reproducing machine, in combination, a motor for actuating a record, a switch in the motor circuit, a latch for holding said switch in closed position, tripping mechanism for operating said latch adjustable with respect to said latch to time the occurrence of the tripping action, said tripping mechanism including two relatively movable members, means for regulating the relative movement therebetween, one of said
- members being adapted to engage said latch, a projection secured to the tone arm and arranged to engage the other member of said tripping member under certain conditions, and a spring for actuating the tripping mechanism to open said switch when one member of said tripping mechanism is engaged by said projection. 20
- Signed at Chicago, Illinois, this 31st day of October, A. D. 1917.

FOREST CHENEY.
